FIG. 1.

FIG. 2.

INVENTOR

Adolph A. Thomas

UNITED STATES PATENT OFFICE

1,997,781

ELECTRIC LAMP

Adolph A. Thomas, New York, N. Y.

Application August 20, 1932, Serial No. 629,598

2 Claims. (Cl. 176—122)

My invention relates to electric lamps, and its object is to provide a novel form of housing for the electric elements of certain kinds of lamps. There is, for example, a type of electric vapor lamp which requires high temperature inside for efficient operation. To maintain this high temperature in the lamp regardless of weather conditions, I provide the glass tube or bulb containing the electrodes with a transparent heat-insulating jacket which forms a permanent structural part of the lamp. This jacket is formed by mounting a second glass bulb in spaced relation over the inner bulb of the lamp, these bulbs being integrally united in a fused joint. The annular space between the two nested bulbs may be evacuated or otherwise rendered heat-insulating. In some instances the jacket space around the inner bulb may contain a light-modifying medium or a cooling medium, the latter being preferably kept in circulation. The outer bulb also acts as a mechanical shield for the inner bulb.

A practical form of my invention is shown in the accompanying drawing, in which—

Fig. 1 is a longitudinal section through my new electric lamp, the base being indicated in dotted outline;

Fig. 2 shows the three glass parts of the lamp separated to illustrate the method of assembly; and

Fig. 3 shows a modified construction in which the space between the two nested bulbs of the lamp is kept filled with a cooling medium in circulation.

The inner bulb or cylinder 10 of glass is formed with an integral annular flange 12 near the base, and the bulb terminates in an extension 13 to which the press 14 is sealed in the usual way. The bulb 10 with its parts 12 and 13 is preferably blown in a mold, and the press 14 is inserted 40 through the opening 15 to the edge of which is fused the edge 16 of the press.

The outwardly projecting flange or shoulder 12 is for the purpose of supporting an outer glass bulb or cylinder 17 adapted to fit over the inner bulb and forming therewith an annular space 18. The edge 19 of glass cylinder 17 is fused to the projecting flange 12 of the inner bulb 10, whereby the two bulbs are integrally and permanently united in concentrically spaced relation. The 50 annular chamber 18 between the two bulbs may be evacuated to the required degree or otherwise treated to form a heat-insulating jacket for the inner bulb. If desired, shock-absorbing pads 20 may be inserted between the bulbs to strengthen 55 this double-walled unit. The pads 20 may be

small pieces of asbestos or the like strung on a wire 21 and placed over the inner bulb 10 before the outer bulb is placed over it. The bulbs 10 and 17 are exhausted of air through tips 22 and 23 or otherwise, and the inner bulb is in some cases filled with gas or vapor before the tip 22 is sealed off, or is otherwise properly treated.

The double-walled lamp unit 10—17 is mounted on a suitable base member 24, which is cemented to the extension 13 and carries contact pins 25 connected to the electrodes in bulb 10. In the basic aspect of my invention, the specific construction and arrangement of the electrodes in bulb 10 are immaterial. By way of example, I have shown a cathode filament 26 and a pair of anodes 15 27—28 between which the cathode is arranged. These electrodes are mounted on four rods or stiff wires 29 embedded in and passing through the press 14, and wires 30 connect the supporting rods 29 to the contact pins 25. Any other 20 practical mounting and electric connections for electrodes 26—27—28 may be used.

Describing briefly the operation of the particular lamp illustrated in Fig. 1, I shall assume that the inner bulb 10 contains a small amount 25 of metallic sodium, which evaporates at high heat to form a glowing vapor. When the filament 26 is brought to incandescence by an electric current, and when a proper voltage is applied to the anodes 27—28, an arc discharge is started and the resulting high temperature in the bulb changes the metallic sodium to a vapor which gives out a brilliant yellow light. To maintain sufficient vapor pressure within bulb 10, it must be kept at a high temperature,—say, between 200° and 35 30 300° C. for sodium vapor lamps. This high temperature is maintained in bulb 10 by means of the vacuum jacket 18, which prevents (or at least reduces to a minimum) the dissipation of heat generated within the bulb 10 during the operation of the lamp.

In some instances, the outer bulb 17 may be used merely as a mechanical shield for the inner bulb 10, and in that case there need be no exhaustion of space 18. This space may also be 45 filled with liquid or gas for modifying the light emitted by bulb 10. For example, if the light coming from bulb 10 is of a certain color which is undesirable in a specific case, that color can be modified or changed by filling the surrounding 50 space 18 with a liquid or gas adapted to alter the color of the original light.

For another use of my double-walled bulb, I may fill the jacket space 18 with a heat-absorbing medium to keep the lamp cool, or to prevent 55

its temperature from rising too high. Such an arrangement would be necessary for high-power tubes in radio systems, where separate water jackets have been heretofore used. In Fig. 3 the outer bulb or cylinder 17 has a pair of open nipples 31 and 32 connected to pipes 33 and 34, respectively. These pipes are in a circulatory system adapted to pass a suitable cooling medium through the jacket space 18, this medium preferably entering through the lower nipple 31 and passing out through the upper nipple 32. Clear water may be used for this purpose, or a transparent gas that has been previously cooled.

In one of the claims I refer to flange 12 as a hollow bead. When the inner bulb 16 comes out of the mold where it is blown, this bead is hollow, as shown in Fig. 2. However, it is possible that in fusing the rim 19 of the outer bulb 17 to the projecting flange 12, some of the melting glass may partly fill in the hollow space of the bead. I do not exclude this possibility when I refer to the bead 12 as hollow.

Although I have herein set forth certain specific constructions to describe my invention, I want it understood that I do not restrict myself to any details unless specified in the appended claims which define the scope of my invention.

I claim as my invention:

1. An electric vapor lamp comprising an integral double-walled unit of glass which consists of an inner bulb and an outer bulb spaced therefrom, the inner bulb having a projecting annular flange to which the rim of the outer bulb is fused, the sealed space between said bulbs having heat-insulating properties, a glass press closing one end of the inner bulb and forming a permanent integral part thereof, four insulated conducting rods or stiff wires mounted in said press and ex-

tending into the inner bulb, a heating element in the inner bulb connected to one pair of said rods, two glow electrodes in the inner bulb connected to the other pair of rods, all of said rods being out of engagement with the outer bulb, a base on which said unit is mounted, and four insulated contact pins projecting from said base and electrically connected to said four conductor rods. 5

2. A heat-insulated electric vapor lamp comprising a single-walled inner bulb of glass permanently sealed and having an integral hollow bead formed between its ends, said bead constituting an outwardly projecting annular flange, an outer glass bulb placed over the inner bulb in spaced relation thereto, the circular rim of 10 said outer bulb engaging said annular flange and being fused thereto, whereby said bulbs form an integral unit of glass which is double-walled from its outer end to said flange, the single wall of said inner bulb extending beyond said double-walled 15 portion of the unit and constituting the base end of said unit, a glass press sealed to said single-walled base end, electrodes supported by said press and extending into said inner bulb in operative relation, said electrodes comprising a 20 cathode and at least one anode, the sealed inner bulb containing a metal adapted to vaporize and glow during the operation of said electrodes, the sealed space between the inner and outer bulbs 25 having heat-insulating properties to prevent dissipation of heat within the inner bulb and thereby maintain the lamp in operative condition, a base attached to said single-walled extension of the inner bulb, and contact pins projecting from said base and electrically connected to said 30 electrodes. 35

ADOLPH A. THOMAS.
